UNITED STATES PATENT OFFICE.

ANDREW J. FALLON, OF CHICAGO, ILLINOIS.

LOCK.

1,423,656.

Specification of Letters Patent. Patented July 25, 1922.

Application filed February 1, 1917. Serial No. 145,836.

To all whom it may concern:

Be it known that I, ANDREW J. FALLON, a subject of Great Britain, resident of Chicago, in the county of Cook and State of Illinois, have invented certain new and useful Improvements in Locks, of which the following is a full, clear, and exact specification.

This invention relates to improvements in locks the case of which is provided on its opposite sides with key holes registering with each other through which the same key is projected for locking and unlocking a door both from the inside and outside of a room.

The object of my invention is to provide such a lock with means whereby on locking the door from the inside the same key may be utilized as a stop, preventing the use upon the outside of the door of a similar or skeleton key retracting the bolt from its locked position and the possibility of its being picked up by any other means.

The further object of my invention is to provide such a lock with means for the purposes above referred to for adapting the use of a key as a stop for both common and tumbler locks.

With these ends in view my invention finds embodiment in certain features of novelty in the construction, combination and arrangement of parts by which the said objects and certain other objects are attained, all as hereinafter fully described with reference to the accompanying drawings, and more particularly pointed out in the claims.

In said drawings:

Figure 1 is a side elevation with the case part in section of a common lock in which my invention finds its embodiment.

Fig. 2 is a vertical section taken on the line 2—2 of Fig. 1.

Fig. 3 illustrates a side elevation of a tumbler lock with the cover of the casing removed for illustrating the adaptation of my invention to a tumbler lock.

Fig. 4 is a vertical section of the same taken on line 4—4 of Fig. 3, and

Fig. 5 is a detailed view of the lock bolt shown in Figs. 3 and 4.

Similar characters of reference indicate the same parts in the several figures of the drawings.

The form of the lock casings 6—6, shown in the several figures of the drawing, including their registering perforations 7—7 for

the stem of knob shanks and their registering key holes 8—8 and keys 9—9 for actuating the bolts 10—10 are common and well known, as are also their bolts and the bolt mechanism shown in the drawings, and need not be described in detail further than to point out, that Figs. 1 and 2 illustrate a plain lock, whereas in Figs. 3 and 4 there is illustrated a tumbler form of lock to both forms of which locks my invention is adapted, as will obviously appear later on, it may be, to other types and constructions of locks provided with a sliding bolt, as is the bolt in the two types of locks referred to.

For adapting my invention to both forms of the locks shown in the drawings their casings are each provided with an additional key hole 11, the eye 12 of which is so located that when the bolts are in their locked position the stem of a key inserted through the eye, will project in a path of movement of the bolts 10 and is not exposed until when the bolts are projected to their locked position, as shown in the drawings.

With the eye 12 of the key hole thus located it will be seen that following the movement of their respective bolts to their locked position on removing the keys from their respective key holes 8—8 and inserting them through the then exposed key holes 11—11, which key holes are inaccessible from the outside of the door, the stem of the key will operate as a stop, preventing the withdrawal of the bolt from its keeper, thereby making it impossible to unlock the door with another and similar key or skeleton key, or to pick the lock by the use of any other device or devices.

In short, my invention provides for the use of a single key for locking and unlocking a door both from its inside and outside, and the use of the same key as a means for preventing the possibility of the retraction of the bolt until the removal of the key from the key hole 11.

As a result of my invention any common and well known form of lock provided with a reciprocating lock bolt is adapted to perform the function and operation of a separate bolt heretofore commonly employed for preventing the opening of a door following the retraction of the lock bolt from its locked position.

In this connection it may be observed that the tumblers for a reciprocating lock bolt are commonly provided with openings adjacent

their free ends in the path of the movement of the bolt which are so located as indicated in Figs. 3 and 4, that the slot of the tumbler adjacent the path of movement of the bolt is covered when the bolt is retracted and uncovered on moving it to its locked position, and when the door is locked and providing an opening through the tumblers past the rear end of the lock bolt and for the passage of a key, across the path of the movement of the bolt, so that on its insertion the key operates as a stop for the bolt in the same manner and with the same result as it does when inserted through the corresponding key hole shown in Figs. 1 and 2.

Among the advantages attributable to the use of my invention is that the additional key hole involves no additional expense, because it may be formed in the casing in casting the same also that the key for locking a door both from its inside and out may be utilized as a stop, preventing the withdrawal of the locking bolt after locking the door from the inside, and that a lock provided with a sliding bolt of any old and well known construction may thereby be adapted to perform the functions of and dispense with the use of an ordinary sliding bolt heretofore commonly employed to prevent the opening of the door following the picking of the lock.

My invention is also adapted for combined locks and latches, wherein there is also another and spring seated latch bolt operated by means of a knob shank passing through the perforation 7-7 of the latch-cases shown in the drawing, and which are so old and have heretofore been commonly employed in connection with sliding bolts and their operative mechanism shown in the drawings, that there seems to be no necessity for their illustration for a clear understanding of the application of my invention thereto.

As a means for preventing any lateral movement of the key on the lock bolt of a tumbler lock when in its operative position as a stop for preventing the retraction of the bolt, the bolt 10 may be recessed (see Fig. 5) as indicated at 13 for the wing of the key. Ordinarily and when the key is confined between projecting lugs, as shown in Fig. 3, such a groove is unnecessary. When my invention is applied to the simple bolt style of lock the key may be turned and locked against accidental displacement, as indicated by dotted lines in Fig. 1.

In conclusion it should be understood that

the projection of a pin through the eye 12 instead of the stem of the key, preventing the retraction of the lock bolt, would not be a substantial departure from my invention notwithstanding that the use of a key hole and a key for the lock is preferred, for the reason that the key serves the same purpose that a pin would, dispensing with its necessity and being superior, the stem of the key being in fact a pin or acting as such and is better adapted for the purpose, also because one object (the key) answers the double purpose of locking the door and preventing the retracting of the bolt from the outside after the door is locked, this being accomplished in the manner already described.

Having described my invention, what I claim and desire to secure by Letters Patent is:

1. A latch bolt, a key therefor and a casing, the inner and outer sides of which casing are each provided with a key-hole located in differing planes and so located with reference to the latch bolt that the latch bolt may be moved by the direct contact of one and the same key therewith to and from its locking position from the outside and secured against retraction from its locking position on the inside.

2. A latch bolt and a casing, the outer and inner sides of which casing are each provided with a key-hole located in parallel planes and in directly reversed positions and adapted for one and the same key for locking and unlocking the bolt from the outside and for securing the bolt in its locked position from the inside by the direct contact of the key therewith.

3. A latch bolt and a casing, the outer and inner sides of which casing are each provided with a key-hole adapted for one and the same key, arranged in reversed position and in vertical parallel planes one of which key-holes projects partly across the path of movement of the bolt, and whereby the key by direct contact with the bolt is adapted for actuating the bolt to and from its locking position from the outside and for positively securing the bolt in its locked position from the inside of a door and against the use of any key from the outside thereof.

In witness whereof, I have hereunto set my hand and affixed my seal, this 30th day of January, A. D. 1917.

ANDREW J. FALLON. [L.S.]
